DUMP DOOR OPERATING MECHANISM

George B. Dorey, Montreal, Quebec, Canada, assignor to Enterprise Railway Equipment Company, Chicago, Ill., a corporation of Illinois

Application December 29, 1950, Serial No. 203,407

10 Claims. (Cl. 105—309)

1

This invention relates to a dump door mechanism for supporting the swinging edge of a pivotally mounted door of the type which is adapted to be lifted from its open position to a partially closed position and automatically latched in such partially closed position with provision for raising the door from said partially closed to a fully closed position by operation of the mechanism.

The objects of the invention among others are: To provide a latch mechanism which when in released position is biased to lie in the path of movement of the door with provision for outward displacement of the mechanism by movement of the door together with provision for the subsequent return of the latch to supporting position beneath the door; to provide a mechanism which in release position is freely swingable toward and away from the swinging edge of the door to engage with and support the door in partially closed position and which mechanism is movable to force the door to fully closed position and in which position it is maintained against swinging movement; and more specifically to provide a jack-knife folding type of linkage mechanism which in its folded position operates as a closed toggle mechanism and when in open position operates as a freely swinging latch member.

The invention also resides in the details of construction concerned with the mechanism supporting bracket and related structure employed to carry out the objects of the invention.

For further comprehension of the invention reference may be had to the accompanying drawings wherein:

Figure 1 is a side elevational view of a portion of a dump car showing as much of the car as necessary to illustrate a discharge opening with one door and the improved mechanism applied thereto, the door being shown in closed position;

Figure 2 is a vertical transverse sectional view taken on a line 2—2 of Figure 1 and showing the door in closed position with the mechanism in supporting position beneath the door and the door shown in open position by conventional dot and dash lines;

Figure 3 is a view similar to Figure 2 except that the mechanism is shown in fully released position with the door in open position.

Figure 4 is a view showing the outer portion of the structure of Figure 2 except that the door is shown in the position where contact is established between the inclined striker surface of the door and latching mechanism, the latter being shown in the pendant released position normally assumed by the mechanism;

2

Figure 5 is a view similar to Figure 4 except that the lifting movement of the door has advanced to show the mechanism as displaced outwardly beyond the path of movement of the door;

5 Figure 6 is a view similar to Figure 5 except that the door lifting movement has progressed to the stage where the supporting shaft has moved to a supporting position beneath the door;

Figure 7 is a vertical elevational view on an enlarged scale of the mechanism during the lifting operation as the shaft enters the retaining slot;

Figure 8 is a detailed longitudinal side view of the shaft assembly;

15 Figure 9 is an end view of the structure shown in Figure 8 as viewed from left to right;

Figure 10 is a side elevational view of the supporting bracket on an enlarged scale;

Figure 11 is a vertical end view of the bracket shown in Figure 10 as viewed from left to right;

Figure 12 is a detailed elevational view of one of the swinging links;

Figure 13 is a vertical end view of the link shown in Figure 12 as viewed from left to right;

25 Figure 14 is a vertical section taken through the outer end of the door and mechanism as seen on a line 14—14 of Figure 2 and illustrating the operating handle.

In said drawings the improved structure is shown as applied to the door of a flat bottom gondola car and the drawings illustrate so much of the car as necessary to show one door and its associated car structure.

Referring to Figures 1 and 2 the car construction includes a longitudinally extending center sill 10 of box girder construction including a vertical web 11, having top and bottom angles as indicated at 12 and 13 respectively and a top cover plate 14. Extending laterally from the center sill in spaced relation are crossbeams, one being shown at 15, each formed with a diaphragm 16 and a top and a bottom cover plate indicated at 17 and 18 respectively. Rising vertically from each end of the crossbeam is a side stake 19 which connects with the side wall designated in this instance by a lower angle 20 and a side sheet 21. The angle 20 includes a horizontally extending flange 22 and a vertically extending flange 23, the former being overlappingly related with the crossbeam top plate 17. The edge of the bottom flange 22 of the side angle 20 in combination with the inner edges of the crossbeam top plates 17 and the edge of the center sill top plate 14 defines a discharge opening 24.

40 Positioned in the discharge opening 24 is a

45

50

dump door 25 which is extended to underlie the plates defining the discharge opening. Said door 25 includes a flat plate 26 having its margins reinforced by flanges as indicated at the sides at 27-27 and at the rear and front edges as indicated at 28 and 29 respectively. The underside of the door is further reinforced by Z-shaped hinge beams 30 extending from the hinge edge to the swinging edge of the door and having one flange 31 riveted to the door with the web 32 outstanding from the door plate and the opposite flange 33 spaced from the door plate. The door is further reinforced lengthwise of the hinge axis adjacent the hinged edge of the door by a Z-shaped beam 34 and the front edge of the door is reinforced by an angle member 35 having one flange 36 riveted to the front flange 29 of the door and the adjacent flange 31 of said angle is spaced from the door plate 26 and substantially in alignment with the flange 33 of the hinge beams 30.

A pair of door extension brackets 38-38 is disposed in spaced relation on the door 25 to provide brackets for cooperation with door operating and supporting mechanisms on the car structure as will be described. Each bracket 38 is of angle shaped formation with walls 39 and 40 secured to the front vertical reinforcement of the door and to the horizontal flanges 33 and 37 of the door beams by rivets as indicated at 41 and 42 respectively. Beyond the door proper the bracket is formed with a projecting nose portion including an upper inclined striker surface 43 and a lower seat 44 for cooperation with door supporting means. Inwardly of the seat 44 there is provided a downwardly extending abutment 45 which constitutes a positioning stop to limit inward movement of the door supporting means and said abutment is braced relatively to the body of the said bracket 38 by ribs 46.

The door 25 is adapted to be manually lifted to closed position and to facilitate this operation a socket 47 is secured to the underside of the door for receiving the end of a removable lifting bar as indicated at 48 in Figure 3. The door 25 in its open position is supported by a suitable door stop as indicated at 49.

The door supporting mechanism includes a bracket 50, Figures 3, 10 and 11, having an upper section including angularly related walls 51 and 52 secured to the car side bottom angle 20 by rivets 53 and extending from said angularly related walls is a wall 54 extending transversely of the car in a direction normal to the hinge axis of the door 25. The wall 54 is provided with an offset portion at 55 and is suitably braced to the upper section by a rib 56. The offset portion 55 is formed with an open ended slot 57 of inverted U-shape to provide inner and outer walls indicated at 58 and 59 respectively and said walls at the outer ends of the slot are flared outwardly as shown at 60 and 61 respectively.

Extending laterally from the wall 54 are lugs 62 and 63 for pivotally supporting a swinging link 64, Figures 12 and 13, on pivot 62 and a locking cam 65 on lug 63. Overlying the said link 64 and cam 65 is a tie strap plate 66 which is riveted in place by rivets 67 extending through the lugs. The swinging link 64 is of hook shaped formation with an indented central portion 68 and at the lower portion thereof it is apertured at 69 for receiving a pivot 70 whereby a door seating element 71, Figures 1, 8 and 9, is hingedly mounted thereon.

The seating element 71 preferably includes a round shaft 72 having arms 73 disposed in spaced

relation on the shaft and fixedly mounted thereon to make a rigid structure. At one end of said structure there is an operating handle 74 having a hub portion 75 secured to the shaft and an open sided socket portion having walls 76 and 77 for receiving an operating bar 78 therebetween, Figure 14, whereby the mechanism is operated.

Each pair of arms 73 includes a hub section 10 79 encircling the shaft 72 and secured to the latter by a rivet as indicated at 80 and extending therefrom are the arms 73 disposed in spaced relation to provide a pair of jaws which straddle the lower portion of the hook-shaped hanger link 64 and through which the securing pivot 70 extends. The structure of the shaft 72 and arms 73 thus constitutes a hinged door supporting element 71 which is eccentrically mounted on its associated hanger links 64 and is swingable about its pivotal axis to function as one of the arms of a jack-knife type of toggle mechanism as will be explained. The hub portion 79 of one of the arms is preferably integrally formed with the hub portion 75 of the operating handle 74.

25 The element 71 in its swinging movement is movable from a closed toggle position as shown in Figure 2 to an opened position as shown in Figure 3 in which latter position it is supported by a lug 82 which forms a limiting stop for engagement with the hub portion 79 of the arm and when in such fully opened position the shaft 72 swings in unison with the hanger links 64, the weight of the shaft 72 operating to bias the swinging link structure to the position shown in Figure 3.

30 The operation of the mechanism may be best understood by following out the sequence of operations involved in the door closing and opening cycle as follows:

35 Assuming the door 25 to be in open position as in Figure 3 with the locking cam 65 in overbalanced released position, and the door seating element 71 gravitated to an open extended position, the operator inserts the lifting bar 48 in the socket 47 of the door to lift the latter. 40 As the door 25 is lifted toward closed position, the inclined striker surface 43 contacts the shaft 72, as shown in Figure 4, swinging the shaft outwardly to clear the door, as shown in Figure 5, and, upon continued lifting movement of the door 25, the latch mechanism swings beneath it supporting the latter in partially closed position as shown in Figure 6. In said partially closed position the shaft 72 is limited in its inward movement with respect to the door by reason of the abutment 45 engaging the shaft 72.

45 Shifting of the door 25 from partially closed to fully closed position is readily effected by a knuckling movement of the door supporting element 71 in a clockwise direction as viewed in Figure 7, said knuckling movement of the shaft 72 being effected by means of the bar 18 being positioned between the walls 76 and 77 of the handle 74 as will be understood. Continued movement of the mechanism in the indicated direction moves the circularly shaped shaft 72 in the open ended slot 57 thereby preventing further swinging movement of the linkage and changing the characteristics of the mechanism from a freely swinging linkage to a toggle folding mechanism.

50 It will be observed that the shaft 72, by reason of the limiting abutment 45 on the door, is maintained in position to enter between the walls 58 and 59 of the slot 57 and the entrance

of the shaft in said slot is facilitated by the flared entrance as provided by the flared surfaces 60 and 61.

The folding movement of the toggle mechanism is completed when the axis 83, Figure 7, of the shaft 72 extends slightly beyond a dead center locking position as indicated by a line 84, Figure 2, joining the pivotal axes of the link in the closed position. The door 25 is thus forced to tightly closed position by a comparatively limited turning effort of the seating element 71 and the cam 65 is then swung in the path of swinging movement of the link 64. The door 25 thus is doubly locked in a securely closed position.

The opening of the door 25 is a reversal of the door closing operation. The operator, after first swinging the cams 65 to released position, inserts the operating bar 78, as shown in Figure 14 between the walls 76 and 77 of the handle 74 and by anti-clockwise movement of the bar swings the door seating element 71 so as to open the toggle mechanism and move the shaft 72 clear of the slotted opening 57 to engage with the lugs 82. The shaft 72 and links 64 then move in unison thereby allowing the withdrawal of the former from beneath the door 25 by continued anti-clockwise movement of the operating bar 78. The releasing of the door 25 is thus accomplished with safety and convenience from a position away from the discharging load.

What is claimed as new is:

1. In a dump car having a pivotally mounted door and door supporting mechanism adjacent the swinging edge of said door, said mechanism including a pair of swinging links pivotally mounted to swing on axes parallel with the axis of the door and a shaft eccentrically mounted on said links to have swinging bodily movement about its axis and assume either a folded toggle locked position with respect to the swinging links to support the door in fully closed position or move to an open extended position to support the door in partially closed position, said shaft being supported wholly by said links and when in extended position being freely swingable in unison with the supporting linkage; and means on the car structure engaging the shaft for holding the linkage against swinging consequent upon movement of the shaft toward final locking position.

2. In a dump car, the combination with a pivotally mounted dump door of mechanism for supporting the swinging edge of the door; a bracket on the car and a two-part folding toggle mechanism including a link pivotally mounted on the bracket and an arm pivotally mounted on the link, said arm having a shaft rigidly connected thereto, said shaft being supported wholly by said folding toggle mechanism with the toggle in open extended position lying below the bracket and swingable therewith to automatically engage with the door to support the latter in partially closed position, said shaft upon folding movement of the toggle to closed position operating to raise the door from partially closed to fully closed position; and an open ended slot in the bracket for receiving the shaft upon closure of the toggle and thereby preventing swinging movement of the toggle mechanism.

3. In a load containing structure having an opening and a door pivotally mounted at one side of the opening and door supporting mechanism adjacent the swinging edge of the door, said mechanism including a bracket secured to the car structure and having a wall in angular relation to the pivotal axis of the door, toggle acting

mechanism pivotally mounted on the wall of the bracket and including a link hanger having a section forming a hook-shaped hanger, said hanger being pivoted at its upper end to the wall and having an arm pivoted at one end to the lower portion of the link, said arm at the end opposite to its pivotal axis having a door seat supported wholly thereby and by said link hanger and arranged to assume a toggle closed position in the indented portion of the hanger to support the door in closed position, and an open ended slot in the wall arranged to receive the door seat upon closure of the toggle and prevent swinging movement of the link.

4. In a load containing structure having an opening and a door pivotally mounted at one side of the opening and door supporting mechanism adjacent the swinging edge of the door, said mechanism including a bracket carried by the supporting structure and having a wall disposed at an angle to the pivotal axis of the door, said wall having an inverted U-shaped open-ended slot; folding toggle link mechanism pivotally carried by said wall and including a hook-shaped link pivotally mounted at one end to the bracket wall above the slot and an arm pivotally mounted at one end to the opposite end of the link and having a shaft fixedly mounted to the opposite end of the arm and supported wholly thereby and by said link, said arm being arranged to knuckle about its pivotal axis with the link and move to a folded position in a toggle closed position in the U-shaped slot and in supporting position beneath the door, said arm being movable to open position to a level below the transverse wall and free of the U-shaped slot; a projecting abutment on the link engaging with the shaft forming a carrying means for the latter to support the shaft below the level of the bracket wall and allow the shaft and its associated link mechanism to swing freely toward and away from the door.

5. In a dump car, in combination with a pivotally mounted dump door, the herein described mechanism for supporting the swinging edge of the door including a bracket mounted adjacent the swinging edge of the door; folding jack-knife toggle link means pivotally mounted on the bracket to swing toward and away from the door, said link means including a swinging link pivotally mounted at its upper end to the bracket and an arm having one end pivotally mounted to the lower portion of the swinging link and a shaft fixedly mounted with respect to the arm and located at the end of the arm remote from its pivotal axis and supported wholly thereby and by said link means, said shaft with the toggle in full open position lying below the bracket and supported by the link and movable in unison therewith, said shaft with the toggle arm in open position being biased to assume a latching position in the path of the door; an inclined striker on the door engaging with the shaft to displace the latter outwardly from its biased position by movement of the door to bring the shaft into engagement with the door for supporting the latter in partially closed position, said shaft upon folding movement of the toggle operating to raise the door from partially closed to fully closed position; and guiding means on the bracket for receiving the shaft and restricting its closing movement to a rectilinear path.

6. In a load containing structure having a discharge opening and a door pivotally mounted at one side of the opening for closing the latter; door mechanism for supporting the door in part-

ly closed and fully closed position and moving the door from said partly closed to fully closed position by operation of the mechanism, said supporting mechanism including a bracket carried by the structure and formed with a depending wall extending in a direction normal to the pivotal axis of the door, said wall having an open ended slot; a link pivotally mounted at one end to the wall of the bracket above the slot, and an arm having one end thereof pivotally mounted on the opposite end of the link, said arm at the end opposite its pivotal axis having a shaft fixedly mounted thereon and supported wholly thereby and by said link, said arm being arranged to knuckle about its pivotal axis and assume a closed toggle position intermediate the axes of the link for supporting the door in closed position with the shaft received and held in the slot, said shaft upon opening movement of the toggle being bodily movable to a position below the level of the bracket; and a stop on the link engaging the shaft to limit opening movement of the toggle mechanism and form a supporting means for the shaft, said shaft in its lowermost position being freely swingable with the link and biased to lie in the path of movement of the door; an inclined striker face on the door disposed to contact the shaft upon lifting movement of the former and displace the latter outwardly to clear the door and allow said shaft to gravitate into supporting position beneath the door to support the same in partly closed position, said mechanism upon folding of the toggle from open to closed position operating to move the door from partially closed to fully closed position.

7. In a dump car having an opening and a pivotally mounted discharge door for closing the opening; door supporting and operating mechanism adjacent the swinging edge of the door, including swinging linkage pivoted adjacent its upper end to the car and having a bodily movable door supporting element hinged to the lower portion of the link and supported wholly thereby, said element being arranged to knuckle about its hinge axis to assume either a toggle locked position for supporting the door in fully closed position or retained in an open position to swing with the linkage and form therewith a swinging latch biased to automatically engage with the door and support the latter in preliminary partly closed position; a seat on the door engaging with the latch element; and an abutment on the door adjacent the seat for limiting inward swinging movement of the latching mechanism.

8. In a dump car having a discharge opening and a pivotally mounted discharge door for closing the opening; door supporting and operating mechanism adjacent the swinging edge of the door including swinging linkage pivoted adjacent its upper end to the car structure and having a bodily movable door supporting element hinged to the lower portion of the linkage and supported wholly thereby, said element being arranged to knuckle about its hinge axis to assume either a

toggle closed position for supporting the door in fully closed position or gravitate to an open position to swing freely with the linkage upon release of the toggle closure and operate as a latch 5 to automatically engage with the door upon closing movement of the latter; means having an opening on the car for receiving the latch element upon closure of the toggle and restraining movement of said element to a substantially rectilinear path; and an abutment on the door arranged to limit inward movement of the swinging latch element and position the latter in line with the opening on the car.

9. In a dump car having a discharge opening and a door for closing the opening pivotally mounted adjacent one edge of the opening; means for supporting the swinging edge of the door including a bracket on the car structure having a wall extending in a plane normal to the hinge axis of the door and linkage mounted adjacent its upper end on said wall to swing toward and away from the door and a door support element hinged to the lower portion of the linkage and supported wholly thereby and movable to a toggle closed position for supporting the door in closed position; means providing an open ended opening in the wall for receiving the door element when in toggle closed position and preventing swinging movement of the linkage; and additional locking means pivotally mounted on the bracket wall to swing in the path of movement of the linkage and thereby lock the entire mechanism.

10. In a car door mechanism for supporting the swinging edge of a pivotally mounted discharge door and including a bracket beyond the swinging edge of the door and having a wall extending in a plane normal to the hinge axis of the door, said wall having an inverted U-shaped opening and a hook-shaped link pivotally mounted above the opening and formed with an intermediate indented portion positioned to align with the opening in the wall; a door seating element hinged to the lower portion of the link and supported wholly thereby and arranged to knuckle about its pivotal axis and enter the U-shaped opening and the indented portion of the link in toggle locked relation with said link; said door seating element being movable to open position beyond the opening and swing with the link in the manner of a latch; an abutment on the link for holding the latch element at a given degree of opening; and supplementary means for locking the mechanism in toggle locked relation including a latching dog pivotally mounted on the wall to move in the path of swinging movement of the link.
